UNITED STATES PATENT OFFICE

101,156

DESIGN FOR AN ELECTRIC COOKING STOVE

Eugene Anthony, Richmond Highlands, Wash.,
assignor to Paramount Heating & Mfg. Co.,
Seattle, Wash., a corporation of Washington

Application January 22, 1936, Serial No. 60,728

Term of patent 14 years

To all whom it may concern:

Be it known that I, Eugene Anthony, a citizen of the United States, residing at Richmond Highlands, in Snohomish County, State of Washington, whose post office address is 315 Wall Street, Seattle, King County, Washington, have invented a new, original, and ornamental Design for Electric Cooking Stoves, of which the following is a specification, reference being had to the accompanying drawing, forming part thereof.

Figure 1 is a plan view of the electric cooking stove, showing my new design. Figure 2 is a front elevation thereof, and Figure 3 an end elevation.

The design is characterized by a leg construction integral with the body of the stove, which is buttressed at the corners to slope downwardly, terminating in a cylinder forming the table-engaging support for the stove. While I have shown a stove comprising two units the number of units is not an essential part of my design.

I claim:

The ornamental design for an electric cooking stove, as shown and described.

Signed at Seattle, King County, Washington,
this 10th day of January, 1936.

EUGENE ANTHONY.
